UNITED STATES PATENT OFFICE.

JOSEPHINE L. HOLT, OF PORTLAND, OREGON.

BUST CONFINER AND REDUCER.

Application filed November 26, 1918. Serial No. 340,810.

To all whom it may concern:

Be it known that I, JOSEPHINE L. Holt, a citizen of the United States, residing at Portland, in the county of Multnomah and State of Oregon, have invented certain new and useful Improvements in Bust Confiners and Reducers, of which the following is a specification.

This invention relates to women's apparel and more particularly to bust confiners and reducers.

The object of the invention is to provide a garment of this character constructed to permit freedom of movement, which is cool and comfortable and will not slip on the wearer's body.

Another object is to construct a garment of this character having an adjustable back section adapted to fit persons of different sizes.

Another object is to provide a device of this character knit and shaped to fit both over and under the bust of the wearer and which is constructed to exert pressure on each side of the bust.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

The accompanying drawing represents: a front elevation of a bust confiner and reducer constructed in accordance with this invention with the parts spread out flat.

In the embodiment illustrated a woven bust engaging member 1 is shown in the form of a strip shaped to fit over and under the bust of the user and having its opposed upper and lower edges reinforced as shown at 2. This member 1 is supported in open operative position by strips of featherbone 3, secured thereto at longitudinally spaced intervals and which extend transversely of the member. Any desired number of these strips may be employed, three being here shown positioned intermediately of the ends of the member and two are preferably used one at each end. The ends of this knit fabric member 1 are provided with a plurality of fastening eyes 4 designed to be connected

with hooks 13 carried by the back member 5 and by means of which the front 1 and back 5 are detachably connected.

The back member 5 which connects the ends of the front member 1 is shown composed of two adjustable sections connected by wide lacing tape 11.

Each of these sections is exactly alike and is constructed of two reinforced members or strips 6 and 7 having lacing eyelets 8 arranged longitudinally thereof adjacent their inner edges to receive a lacing cord 9. The outer edges of the strips 7 are equipped with the hooks 13 for co-operation with the eyes 4 on the front member, while the inner edges 70 of the member 6 carry loops 10, suitably positioned to receive the lacing tape 11.

While the back member is shown herein composed of double sections adjustably connected by the tape 11, it is to be understood that single sections may be employed if found desirable.

By so constructing this bust reducer about a $2\frac{1}{2}$ " pressure on each side will be effected at the points where the front member 1 is connected with the back section. This $2\frac{1}{2}$ " pressure on each side makes about 5" of pressure for reducing the bust and is the secret of success of this article. For instance, if the actual bust measure is 48" the combined front and back sections are made 43".

From the above description it will be seen that the bust confiner 1 which may be made of either elastic or inelastic cord knit or crocheted to fit the figure and which is connected by the adjustable back section 5 may be used by persons of different sizes by lengthening or shortening the tape 11 which is secured in adjusted position by the buckles 12 and the members 6 and 7 of the sections may be adjusted by the lacing cords 9, loops 14 being suitably formed in said cords for this purpose.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and

2
that such changes may be made as are within the scope of the claimed invention.

Having thus fully described my invention, what I claim to be new and desire to secure by Letters Patent is:

1. In combination, a back section, a bust supporting element and means for attaching the bust supporting element to the back section in different vertical positions thereon.
2. A garment of the class described comprising a fabric strip shaped to fit the bust of the wearer and provided with longitudinally spaced transversely extending reinforcing elements, a back section composed of two members having smooth elongated loops along their opposite edges, a flat lacing tape threaded through said loops and provided with buckles to secure it in adjusting position and cooperating elements carried by the back members and the ends of the front members whereby said front

member may be detachably engaged with the back section.

3. A garment of the class described comprising a woven strip shaped to fit over and under the bust of the wearer, a back section, means for supporting the woven strip in different vertical positions on the back section. 25 30

4. A garment of the class described comprising a woven strip shaped to fit over and under the bust of the wearer, a back section, means for attaching the woven strip to the back section in different vertical positions thereon, and means for exerting pressure at the opposite ends of said strip on the body of the wearer. 35

In testimony whereof I affix my signature in presence of two witnesses.

JOSEPHINE L. HOLT.
